UNITED STATES PATENT OFFICE.

WILLIAM HENRY WORTH, OF PETALUMA, CALIFORNIA.

SCREW AND TOGGLE-LEVER PRESS.

SPECIFICATION forming part of Letters Patent No. 301,038, dated June 24, 1884.

Application filed May 1, 1884. (No model.)

To all whom it may concern:

Be it known that I, WILLIAM H. WORTH, of Petaluma, county of Sonoma, and State of California, have invented an Improvement in 5 Screw and Toggle-Lever Presses; and I hereby declare the following to be a full, clear, and exact description thereof.

My invention relates to improvements in 10 cider, cheese, wine, or other similar presses in which double toggle-levers are employed, with a right-and-left-hand screw-shaft, by which they are operated; and it consists in a means for keeping the power and strain of the press in a right line, so as to avoid all cramping and warping of the parts.

Referring to the accompanying drawings for a more complete explanation of my invention, Figure 1 is a view of a press containing my improvements. Fig. 2 is a detached view 20 of the two lower levers, showing the links by which a parallel motion is produced.

A A are the upper and lower beams of the frame, united by stout rods B.

C is a platform, upon which the material to 25 be pressed is placed.

D is a follower-beam.

Upon the upper beam A and upon the follower-beam are fixed the heavy irons E, to which the upper and lower ends of the toggle-levers F are pivoted by means of bolts passing through holes at G.

H H are heavy nuts having right and left hand screw-threads to fit upon the corresponding threads of the horizontal screw I.

35 By the operation of this screw the ends of the toggle-levers, which are pivoted to the nuts H, are caused to approach to or recede from each other as the screw is rotated, and thus raise or force the follower down, the upper beam A resisting the upward thrust of the levers.

The screw may be operated by pawl-and-ratchet levers J upon opposite ends, and it may also have a light wheel, K, fixed to one 45 end, so that it may be revolved more rapidly when it is desired to raise the follower up. In order to keep the power of the toggle-levers operating in a direct vertical line or at right angles with the horizontal screw, I employ 50 links L, which unite the lower ends of the

two lower levers and the upper ends of the two upper levers, as follows: These levers have lugs or projections M and N. The projection N, at the lower end of the lever F, Fig. 2, is at a point a short distance inside of 55 an axis or line passing longitudinally through the pin-holes which are at each end of the lever, so that a line drawn from the pivot G through the pivot-hole of N would make an angle of from twenty to thirty degrees with a 60 line forming the axis before described. The lug M is perforated for a pin at the same distance from G with the pin-hole of N, and at right angles with it from the hole G. The links L are connected to the lug M of one lever, and the opposite lug, N, of the other, the 65 two links crossing each other, as shown in Fig. 2. It will be seen by this construction that the toggle-levers F F are so united that any motion imparted to the outer ends of either 70 would be communicated equally to the other lever, and that the movements of each would thus be made so nearly equal as to impart a direct vertical movement to the lower D.

75 By having the pin-holes in the lugs N made inside of the line of the axis of the levers, as before described, I am enabled to equalize the movement of the lugs M and N, so that whether the levers be widely separated or moved up 80 near together by the action of the screw, the movement of the lugs M and N about the pivoted points G will be equal, and consequently there will be no strain upon the links L by reason of one set of lugs moving faster than 85 the other at any point of their rotation about this pivotal point of the levers.

Having thus described my invention, what I claim as new, and desire to secure by Letters Patent, is—

1. In a screw and toggle-lever press, means for producing an equal and parallel movement of the parts, consisting of lugs projecting inwardly from the outer ends of the levers and united by links, which cross each other so as 95 to connect the upper lug of one lever with the lower lug of the other, substantially as herein described.

2. The toggle-levers F, having the lugs M and N, with the crossed links L, uniting the 100

links of one with those of the other, substantially as herein described.

3. The toggle-levers F, pivoted at G, having their outer ends united to the nuts by which 5 they are caused to approach or recede upon the horizontal screw, and lugs N, perforated at points inside of the line forming the axis of the levers, the lugs M at right angles with

them, and the connecting-links L, substantially as herein described.

In witness whereof I have hereunto set my hand.

WILLIAM HENRY WORTH.
